Inventor:

Rufus Waterhouse.

By # UNITED STATES PATENT OFFICE.

RUFUS WATERHOUSE, OF NEW YORK, N. Y.

DESIGN FOR A NECKSCARF.

SPECIFICATION forming part of Design No. 15,921, dated March 3, 1885.

Application filed December 22, 1884. Term of patent 3½ years.

To all whom it may concern:

Be it known that I, RUFUS WATERHOUSE, a citizen of the United States, residing at New York, in the county and State of New York, have invented and produced a new and original Design for Neckscarfs, of which the following is a specification, reference being had to the accompanying drawing, forming part thereof, in which it is represented in perspective.

The body of my scarf is represented of hexagonal form, having a top, *a*, upper sides, *b b*, inclined outward, lower sides, *c c*, inclined inward, and a spreading bottom, *d*, extending laterally beyond the top. The inner portion of the body is divided by folds of *Y* form, which leaves an upper portion of triangular form and two side portions of pentagon form.

The lower parts of the side portions are shown as gathered together by a band, *e*, to represent 20 sent folds *g g*, and beneath the band is a spreading apron, *f*, whose lower ends may be of any desired shape.

h represents an ordinary neck-strap.

I claim—

The design for a neckscarf, as shown and described, consisting of a body of hexagonal form, having a top, *a*, upper sides, *b b*, inclined outward, lower sides, *c c*, folds of *Y* form, and a bottom, *d*, extending laterally beyond the 30 top, a band, *e*, and a spreading apron, *f*.

RUFUS WATERHOUSE.
